UNITED STATES PATENT OFFICE.

WILLIAM H. HURLEY, OF NEW HAVEN, CONNECTICUT, ASSIGNOR OF ONE-HALF TO
JAMES M. KEANE, OF NEW HAVEN, CONNECTICUT.

KNIFE HANDLE.

Application filed June 28, 1922, Serial No. 571,564. Renewed March 31, 1925.

To all whom it may concern:

Be it known that I, WILLIAM H. HURLEY, citizen of the United States, residing at New Haven, in the county of New Haven and 5 State of Connecticut, have invented certain new and useful Improvements in Knife Handles; and I do hereby declare the following to be a full, clear, and exact description of the invention, such as will enable 10 others skilled in the art to which it appertains to make and use the same.

This invention relates to table cutlery, and particularly to knife handles, its object being to cheapen the knife construction by 15 avoiding many of the expensive operations incidental to forged knives wherein the blade and handle are of integral construction.

The improved construction consists in 20 employing a metal tube to form the handle and securing the same to the tang of a tempered steel blade. A tube of wood, or other like non-metallic material smaller in diameter than the interior of the metal tube, is 25 inserted therein and said wooden tube and intervening space filled with lead or other like molten metal, and shape the metal tube to form the handle, neck, bolster and rim.

Referring to the accompanying drawings, 30 wherein the same figures and letters of reference indicate like parts throughout the several views:

Figure 1 represents a broken blade;

Figure 2 is a sectional view of the metal tube or shell, broken view of the blade with its tang inserted in the tubular handle, also a view of the wooden tube or core within the metal tube;

Figure 3 is an end view of Figure 2 looking 40 in the direction of arrow *x*;

Figure 4 is an end view of the metal tube and sectional view of the blade on line 4—4 of Figure 2;

Figure 5 is a sectional view of the tubular handle, wood core and lead filler, broken edge view of the blade and insertable plugs in the blade end of the tubular handle;

Figure 6 is an enlarged broken edge view of the blade, enlarged broken sectional view of the tubular handle shaped to form the neck, bolster and rim, and sectional view of the wooden tube and filling material;

Figure 7 is an enlarged broken side elevation of the blade, enlarged broken sectional view of the handle and filling material, and

an enlarged broken view of the wooden tube embracing a part of the tang of the blade;

Figure 8 represents a side elevation of a finished knife;

Figure 9 is an edge view of Figure 8; 60

Figure 10 is an enlarged cross sectional view of the finished handle on line 10—10 of Figure 8, and

Figure 11 is a detail view of the wooden tube or core. 65

The blade 1 is provided with a tang wherein the part 2 is preferably slightly wider than the part 3. The part 2 is narrower than the blade so as to form the shoulders 4. The mouth of the tube 5 is a trifle 70 narrower than the part 2 of the tang, so that, when the tang is forcibly entered in the tube, the mouth will assume the elliptical shape shown in Figure 4, with the end of the tube firmly abutting against the shoulders 4 and the ends of the ellipse on a line with the front and rear edges *a*, *b*, of the blade.

After the blade is firmly seated in the metal tube, the hollow wooden tube 6, Figure 11, is inserted in the opposite end of the metal tube with its kerf 7 embracing, Figure 2, a portion of the tang of the blade, and it is thus held in a central position with respect to the interior of the metal tube. 80

The lower end of the tube 5 is partially closed as shown in Figure 5, and the metal plugs 8 are inserted a short distance within the metal tube and are shaped to fill its elliptical mouth 9, Figure 4, on each side of the blade, as shown in Figure 5. 85

Molten lead 10, or other like molten metal, is then poured into the opposite end of the metal tube, passing through the central hole 11 of the wooden tube, and about said tube, filling the space within the metal tube to the plugs 8, leaving, however, a small vacant space *c* at the opposite end for the purpose to be hereinafter more fully explained. 95

As soon as the molten metal has cooled, 100 the plugs 8 are removed and the metal tube is given the proper shape to form the handle. This is done under pressure in a properly shaped die—not shown—to form the elliptical handle 12, bolster 13, rim 14, and neck 15. The pressure exerted by the die in the direction of arrow *d* to form the neck 15 will force the metal filling 10 well into the rim 14, and also compress the lips 15^a under which there is no filling material, 110

firmly against the sides of the blade and so reduced by compression as to give the impression that the blade and neck are integral.

- 5 In forming the bolster 13, the side pressure of the die will force the metallic filling well into the groove 16 of the tank, Figure 7, and thus lock the blade firmly to the handle.
- 10 If the metal tube was entirely filled with lead or other like molten metal, it would not readily compress to permit the outer metal shell or tube assuming the proper elliptic shape required for the finished handle, but
- 15 would be forced out of the open end of the tube and thus interfere with the closing of said end. To overcome this, the compressible wooden tube is introduced to compensate for the non-compressibility of the metal
- 20 filler. In applying the necessary pressure to give the elliptic shape to the handle, the several elements will naturally assume the appearance shown in Figure 10. The applied pressure of the die will force the metal filling within the wooden tube out in quantity sufficient to fill the space *c*, Figure 5, and not interfere with the closing of that end of the handle. Under this pressure, the metal filler will also be forced out of the opposite end of this wooden tube to fill any vacant space occurring about the tang of the blade, and also fill the hole 17 of the tank and thus add an additional locking grip for the blade.
- 25 A knife, constructed as above described, has, when finished, the appearance of being forged. One of the principal features that give this resemblance is, that, like a forged knife, the edges *a*, *b*, of the blade are on a
- 30 line with the elliptical ends of the handle, which is due to shoulders 4 of the blade, whose depth is practically equal to the thickness of the metal shell, so that, when the knife is finished, the edges of the blade near
- 35 the handle are on a line therewith. Thus,

while having the appearance of a forged knife, it is much cheaper to construct, and just as durable.

Having thus described my invention what I claim is:

1. A knife of the character described, comprising a blade having a shouldered tank, a metal tube into one end of which the tang is forcibly seated against said shoulders, a non-metallic tube located within the metallic tube, molten metal injected into both tubes, and said tubes and contents subjected to pressure suitable to form a closed handle having a neck bolster and rim. 55

2. A knife of the character described, comprising a blade having a shouldered tang, a metal tube whose walls equal the depth of said shoulders, said tang forcibly entered into the mouth of said shell to give said mouth an elliptic form with its ends coinciding with the edges of the blade, a non-metallic tube located within the metal tube and of smaller diameter than the interior of the metal tube, molten metal injected into both tubes, and said tubes subjected to pressure suitable to form a closed handle having a neck, rim and bolster. 60

3. A knife of the character described, comprising a shouldered tang, a metal tube having an elliptical mouth embracing the tang whose ends abut said shoulders and coincide with the edges of the blade, a smaller non-metallic tube within the metal tube and guided on the tank, molten metal injected into both tubes, temporary means for closing the elliptical mouth of the outer tube, and said tubes subjected to pressure suitable to form a closed handle having a neck, rim and bolster. 75

In testimony whereof I affix my signature.

WILLIAM H. HURLEY.
